UNITED STATES PATENT OFFICE.

HARRY ANTHONY ORME, OF WASHINGTON, DISTRICT OF COLUMBIA.

AEROPLANE.

1,153,248.

Specification of Letters Patent. Patented Sept. 14, 1915.

Application filed April 15, 1912. Serial No. 690,791.

To all whom it may concern:

Be it known that I, HARRY A. ORME, a citizen of the United States, residing at Washington, in the District of Columbia, 5 have invented a new and useful Improvement in Aeroplanes, of which the following is a specification.

This invention relates generally to aeroplanes, and more particularly to certain improvements whereby an exceedingly strong, durable and light machine is provided.

One of the objects of my invention is to provide a machine in which the planes are arranged and maintained in fixed relations 15 at all times thereby avoiding the warping or twisting of the planes at the edges thereof.

Another object of the invention is to provide a machine in which the rudders will be 20 employed not only for the purpose of steering the machine but also for the purpose of balancing or maintaining the equilibrium of the device and whereby shorter and easier turns are made possible.

25 Another object of the invention is to provide a machine in which the forward traveling wheel usually employed is dispensed with and likewise the forward elevating planes, and a still further object is to so 30 construct and arrange the skids that in case of sudden descent the machine on reaching the ground will not stick its "nose" into the ground, but will either bound off or turn over, producing slight damage but avoiding 35 the complete demolition of the machine and serious injury to the operator.

Another object of the invention is to provide a combined equalizing and elevating plane at the rear for the purpose of enabling 40 the machine to get into the air or rise in a very short traveling distance.

Another object of the invention is to provide movable supporting wheels at the side which serve to support the machine during 45 the starting operation but which are thrown up out of the way during the landing operation permitting the machine to land upon the skids or runners, this feature of the movable supporting wheel being the subject matter of a patent granted to me and numbered 50 1,065,389 and utilized in the present form of machine in connection with the improved construction of skids.

With these various objects in view and 55 also with certain other objects as will appear hereinafter, my invention consists in

the novel features of construction, combination and arrangement all of which will be fully described herein and pointed out in the claims.

In the drawings forming a part of this specification: Figure 1 is a perspective view of my improved construction of flying machine. Fig. 2 is a sectional plan view taken about midway between the two planes, the forward portions of the skids being omitted. Fig. 3 is a detail view taken on the line 3-3 of Fig. 2. Fig. 4 is a sectional elevation on the line 4-4 of Fig. 2. Fig. 5 is a sectional view of the fixed and movable rear planes. Fig. 6 is a sectional plan view on the line 6-6 of Fig. 5, and Fig. 7 is a detail end elevation showing a portion of one of the rudders.

In carrying out my invention I employ an upper plane A and a lower plane B, said planes being constructed upon a definite curve from front to rear and spaced apart and held in fixed relation from end to end by means of stanchions or posts C, and similar posts or stanchions C also serve to support the planes above the skids or runners D, said skids or runners extending forwardly a short distance and then curve upwardly as shown at D', and then carried rearwardly and upwardly and connected to the upper plane and stanchion as shown, suitable braces or struts D² being employed to strengthen the peculiarly shaped skids.

A rearwardly extending frame E is connected to the upper and lower frames at the central portions thereof, this frame being skeleton in form as shown, and at its rear end has a horizontal plane F hinged thereto, said plane F being movable up or down as indicated in dotted lines in Fig. 4, and directly in advance of the hinged plane F, and also connected to the rear end of the skeleton frame E is a fixed horizontal plane G, this fixed plane being steadied by guy wires G' extending from said plane, as most clearly shown in Figs. 1 and 2.

The movable plane F is operated by wires F' and F² passing through guides F³ and F⁴ respectively, upon the top and bottom of the rear end of the frame E said wires F' and F² being connected to opposite ends of a hand lever F⁵ arranged adjacent the seat of the operator and by means of which the rear plane F can be raised and lowered as desired by simply moving the hand lever back and forth to the proper position.

Guide pulleys F^3 are arranged upon the lower frame to guide the wires F' and F^2 .

It will of course be understood that the rearwardly extending frame is provided 5 with suitable braces in order to impart rigidity without materially adding to the weight of said frame.

Between the upper and lower planes adjacent the ends thereof I arrange the rudders H , each rudder comprising a vertical blade or wing H' and a horizontal blade or wing H^2 , the vertical blade or wing being adapted to turn upon its vertical axis and each horizontal blade or wing turns upon 15 its horizontal axis independent of the movement of the vertical wing or blade, that is the horizontal wing or blade can be moved up or down without moving the vertical blade, but when the vertical blade is moved 20 from side to side it carries with it of course the horizontal wing or blade.

The broad features of this particular construction of rudder are embodied in my Patent 1,074,063, and it will be understood 25 that the vertical wing or blade is slotted as shown at H^3 in order to permit the movement of the horizontal blade or wing, this movement of the horizontal blade or wing being accomplished by wires H^4 extending 30 from said horizontal blade or wing through or around suitable guides H^5 to the opposite ends of a hand lever H^6 and the rudder as a whole is turned from side to side by means of wires I , connected to the horizontal wing 35 or blade adjacent the opposite ends thereof, said wires extending through and around suitable guides I' and connected to the opposite ends of a hand lever I^2 . It will also be understood that the rudders move in unison, 40 that is when the hand lever is operated to raise or lower the horizontal wing H^2 upon one side the horizontal wing H^2 upon the opposite side will be oppositely operated and when the other hand lever is operated to 45 turn one rudder to the right or left the other rudder will be correspondingly operated. It will thus be understood that both rudders act simultaneously, the vertical wings always turning in the same direction while 50 the horizontal wings are so connected one to the other that they turn in opposite directions, that is when the horizontal wing upon one side moves up the horizontal wing upon the opposite side moves down and by means 55 of this construction shorter and more even turns are made possible. Any suitable construction of engine may be employed and arranged upon one side of the operator and the power of this engine is connected to the 60 two propellers K through the medium of shafts, sprockets and gearing constructed and arranged in accordance with the power

mechanism illustrated, described and claimed in my application filed July 15, 1911, Serial Number 638,699.

65

In order to render the device easily transportable I preferably construct the planes of three parts each, namely, a central portion and two end portions and these portions are securely connected by means of connecting plates L , which are clearly shown in Figs. 1 and 2. By means of the rearwardly extending frame carrying the fixed and movable horizontal planes at its rear end I am able to guide the machine off the ground 70 in a remarkably short space of time and distance, the movable plane being raised up to cause the machine to quickly mount upwardly. During the flight of the machine this movable plane can be raised or lowered 75 for the purpose of causing the machine to move up or down as desired. By having the main planes fixed with relation to each other from end to end at all times and providing the compound rudders between the ends of 80 these planes I provide a machine of exceeding lightness, quick in action, and unusually stable. It will thus be seen that I provide an improved construction of aeroplane 85 capable of carrying out and accomplishing 90 all of the operations hereinbefore referred to.

What I claim is:

1. In an aeroplane, the combination with main upper and lower fixed planes spaced apart, of vertical rudders pivoted between 95 and extending to the rear of the fixed planes and adjacent the ends of said planes, balancing planes moving with said rudder planes and adapted to swing independent of the rudder planes and at an angle to the plane of 100 movement of said rudder planes, said balancing planes extending to the rear and beyond the ends of the fixed planes, and means for controlling the rudder and balancing planes.

2. In an aeroplane, the combination with 105 fixed upper and lower planes spaced by front and rear posts, of vertical rudders carried by said rear posts and adapted to swing from side to side, vertically movable balancing planes carried by the rudders and projecting beyond the fixed planes, a rearwardly extending frame, a fixed plane arranged horizontally in said frame and in a plane midway the upper and lower first mentioned planes, and intermediate said 110 rudders, and a vertically movable plane arranged in the rear of the last mentioned fixed plane and forming when in a horizontal position a continuation of the fixed plane.
